FIG. 1

FIG. 1 is a front, top and right side perspective view of a juke box showing my new design;

FIG. 2 is a front elevational view;

FIG. 3 is a left side elevational view; and

FIG. 4 is a top plan view.

The rear is plain and unornamented, and the pattern partially shown on the lower front panel in FIGS. 1, 2, and 4 is continuous over the whole of that panel.

I claim:

The ornamental design for a juke box, as shown and described.
